UNITED STATES PATENT OFFICE

2,605,006

APPARATUS FOR CHARGING METAL INGOTS
INTO MOLTEN METALWilliam J. Barnes, Swarthmore, Pa., assignor to
E. I. du Pont de Nemours and Company, Wil-
mington, Del., a corporation of Delaware

Application June 5, 1951, Serial No. 230,025

10 Claims. (Cl. 214—18)

1

This invention relates to apparatus for charging metal ingots into molten metal and more particularly for charging metallic lead, either in large single ingots or in stacks of small ingots, into a body of molten lead in a melt pot.

Lead and other metals are frequently melted and maintained in molten condition in heated pots from which the molten metal is continuously or periodically withdrawn for use in chemical and other processes. When the body of the molten metal has been lowered to a predetermined level, it is necessary to add further amounts of the solid metal to the body of molten metal to replace that which has been withdrawn. Various mechanical devices have been proposed for lowering the solid metal into the body of molten metal, but, in general, such devices have the disadvantage that they have moving parts which are brought into close proximity to the molten metal and which are soon rendered inoperative by the splashing of the molten metal thereon. Also, such devices generally have the disadvantage that they can be used for charging ingots of only a small range of sizes, and cannot be used for charging both large and small ingots, such, for example, as a single large 3800 pound ingot or an equivalent charge of 100 pound ingots. One type of device, which has been employed, comprises a 3-wheel type of "clamshell" bucket operated from an overhead crane. Such device exposes moving parts, operating under only slight forces, to the splash of molten metal which freezes thereon, rendering the device inoperative until the metal is removed by a separate operation, such as melting or chipping. Another device is an ice tong type of grapple, operated from an overhead hoist, which handles ingots of only a limited size, and considerable difficulty is experienced in disengaging the tongs from the ingot. Such types of devices cannot well be enclosed in a hood, whereby there is danger of splashing personnel with molten metal and of subjecting them to obnoxious and dangerous fumes and gases.

It is an object of the present invention to provide new and improved apparatus for charging metal ingots into a body of molten metal in a melt pot. Another object is to provide an apparatus of such character which can conveniently be enclosed in a protective hood. Still another object is to provide an apparatus of such character which will not be rendered inoperative by splashing metal. A further object is to provide an apparatus of such character which will permit the charging of ingots of a wide range of sizes, from a single large ingot to a plurality of small ingots.

2

Still further objects are to advance the art. Other objects will appear hereinafter.

The above and other objects may be accomplished in accordance with my invention which comprises in combination an elevator for slowly lowering an ingot carrier from a loading position above the melt pot to a dumping position at which the carrier is partially submerged in the body of molten metal for from about $\frac{1}{6}$ to about $\frac{2}{3}$ of its height and to then tilt the carrier backward to dump the ingots, an ingot carrier pivotally suspended from the bottom of the elevator, dumping means cooperating with the elevator to tilt the carrier backward as it reaches the dumping position, and backing means for preventing the ingot carrier from tilting when it is in loading position; the ingot carrier consisting essentially of two parallel spaced elongated vertical side members rigidly connected together and having smooth 10 straight back surfaces for most of their height, a rigid longitudinally flat horizontal platform at the lower ends of the side members, the pivotal suspension for the ingot carrier including a transverse pivot at substantially the level of the upper 15 ends of the side members above substantially the center of gravity of the carrier; the dumping means comprising a transverse dumping bar projecting from the side members adjacent the upper ends thereof and spaced to the rear of and extending 20 parallel to the pivot, and at least one stationary dumping hook having a transverse notch in its upper surface above the body of molten metal at a distance equal to from about $\frac{5}{6}$ to about $\frac{1}{3}$ of the height of the ingot carrier and in the path 25 of only the transverse dumping bar; and the backing means comprising at least one stationary backer bar above the dumping hook and opposite to and abutting the vertical straight back surfaces 30 of the ingot carrier side members near the lower ends thereof when the ingot carrier is in loading 35 position. Preferably, the platform of the carrier will be in the form of spaced longitudinally extending horizontal rails. Also, preferably, a stationary bumper will be provided slightly to the 40 rear of the ingot carrier when the carrier is in its lowermost position for engaging the load and aiding 45 in its discharge from the carrier.

My invention will be more readily understood from the following description taken with the accompanying drawings, in which:

Figure 1 is a front view of my preferred form of charging apparatus, with parts broken away and parts in section for clearness of illustration;

Figure 2 is a side view of the apparatus of 55 Figure 1, with parts omitted, and showing two

positions of the ingot carrier and of the elevator therefor; and

Figure 3 shows a modified form of ingot carrier.

The charging apparatus is positioned near one edge of the melt pot of which a small portion is shown at 10. The melt pot is provided with a cover 11 provided on its upper surfaces with reinforcing brackets 12 and has an opening over which the charging apparatus is supported. In the embodiment of Figures 1 and 2, the charging apparatus comprises an ingot carrier 14 consisting of 2 parallel spaced vertical side members each substantially in the form of a vertically elongated square C having a vertical back portion 16, a lower forwardly extending horizontal portion 18, and an upper forwardly extending horizontal portion 24. The vertical portions 16 have smooth straight back surfaces extending vertically for most of their height. The lower portions 18 have upper longitudinally flat horizontal platform surfaces which form a platform, consisting of two spaced longitudinally extending rails, for supporting one or more ingots of lead 19 and are rigidly connected together by spacer bars 20, the upper edges of which are below the horizontal plane of the upper platform surfaces of the rails 18. Also, the portions 16 are connected together near their upper ends, preferably by a spacer bar 22. The ingot carrier 14 is pivotally suspended from the bottom of an elevator by a transverse pivot 26 extending through the upper horizontally extending portions 24 of the side members intermediate the ends thereof and above substantially the center of gravity of the carrier.

The pivot 26 is carried by the lower ends of spaced arms 28, depending from the horizontal connecting plate 30 of an H-shaped crosshead, of which the vertical side members are indicated at 32. The crosshead is supported at the lower end of the piston rod 34 of a pneumatic cylinder 36 by a universal joint 38. The cylinder 36 is supported on a top plate 39 at the top of a supporting frame 48. The plate 39 is reenforced by beams 40 below the cylinder 36 and a plurality of braces 42 supported on the melt pot cover, only one of such braces being shown for purposes of illustration.

The crosshead is provided at each of its ends with a plate 44 carrying a vertically elongated narrow guide block 46 fitting loosely between parallel spaced vertical guide members 50 which extend from the top plate 39 downward to below the top of the melt pot. The crosshead and the operating mechanism therefor constitute the elevator.

Preferably, the forward ends 52 of the upper horizontal portions 24 of the ingot carrier carry stop-lugs 54 which engage arms 56 extending forwardly from the crosshead, so as to ensure that the ingot carrier will not accidentally tilt forwardly. The stop-lugs may be carried by the arms 56, or eliminated by lowering the arms 56 to cause them to contact the ends 52. Other forms of stop means may be substituted. The stop means may be omitted entirely, but will usually be desired to aid in holding the carrier firm during loading operations.

A round dumping bar 58 passes transversely through the side members 16 adjacent the upper rear corners thereof and has its ends projecting outwardly beyond the side members. Such dumping bar is parallel to the pivot 26. Spaced dumping hooks 60 are supported by brackets 62 firmly secured to the melt pot cover and are provided

in their upper edges with notches for receiving the dumping bar 58. Each of the notches has a downwardly inclined surface 64 which extends downwardly and forwardly at an angle of about 40° from the horizontal for a few inches from the point where it first engages the dumping bar to the forward lower portion of the notch 66. The length and inclination of the surface 64 will be dependent upon the distance between the pivot 26 and the dumping bar 58 and upon the angle through which the carrier is tilted. The dumping hooks are spaced apart by a distance slightly greater than the width of the ingot carrier so that the ingot carrier can pass downwardly between them until they are engaged by the projecting ends of the dumping bar. The notches in the dumping hooks are positioned above the body of molten metal in the melt pot at a distance equal to from about $\frac{1}{6}$ to about $\frac{1}{3}$, preferably about $\frac{1}{2}$, of the height of the ingot carrier and in the path of the outwardly projecting ends of the dumping bar.

A bumper is provided for aiding the discharge of the load from the ingot carrier. This consists of two spaced upwardly and backwardly extending elongated support members 68 secured to the under surface of the melt pot cover and provided with braces 70, a spacer member 74 and a bumper bar 72 secured to the lower ends of the members 68. This bumper is of a width slightly less than the distance between the side members 16 of the ingot carrier and the bumper bar 72 is of a height less than $\frac{1}{2}$ the height of such side members. Such bumper bar is positioned slightly above and to the rear of the horizontal platform surfaces of the carrier when such carrier is in its lowermost un-tilted position and between the vertical planes of the side members 16 of the carrier.

A backer bar 76 is carried by spaced brackets 78 supported on the cover of the melt pot. Such backer bar extends transversely of the ingot carrier and is positioned opposite to and abutting the vertical straight back surfaces of the ingot carrier near the lower ends thereof when the carrier is in loading position, so as to prevent tilting of the carrier during the loading thereof.

Usually, the ingot carrier and the rest of the cooperating mechanism which extends above the melt pot cover, except for the pneumatic cylinder 36, will be enclosed in a hood, indicated generally at 80. Such hood will have a door and a vent for gases, not shown.

The various parts of the apparatus will usually be made of steel. However, it will be apparent that they may be made of other materials of sufficient strength and melting point to withstand the stresses and heat involved.

The operation of the apparatus of Figures 1 and 2 will now be described, assuming that molten metal has been removed to the extent where it is desired to add solid metal to replace that removed, the upper surface of the body of molten metal then being at the predetermined "lower liquid level" shown in Figure 2 of the drawings. The elevator and ingot carrier will be in the loading position shown in solid lines in Figures 1 and 2 and the solid metal 19, in the form of a single large ingot or of a stack of small ingots, will be loaded on the platform rails of the carrier. During such loading, the stop-lugs 54 will prevent the ingot carrier from tilting forwardly and the backer bar 76 will prevent the carrier from tilting backwardly. The stop-lugs 54 are not essential, but will usually be desired for complete

safety. After the load of solid metal has been placed in the carrier, the door to the hood will be closed and the elevator mechanism will be set in operation to slowly lower the carrier.

During the downward motion, the straight back edges of the carrier will slide over the backer bar 76 which will ensure that the carrier is not tilted backward until the upper ends of such straight edges pass below the backer bar. This results in a scraping action which removes any metal which may have been splashed on the bearing surfaces or keeps it at an insignificant thickness for long periods of time. Also, in the structure as shown, the edge of the melt pot cover in back of the carrier acts as a second backer bar and further prevents tilting of the carrier until it reaches the dumping position. Additional backer bars may be employed in place of or on the edges of the melt pot cover, if desired. However, it is not necessary to have the edge of the melt pot cover abut against the rear edges of the carrier or to provide additional backer bars at this point. The load usually will not be very far off center due to the construction of the carrier and the size of the loads employed, whereby the carrier will usually hang nearly vertical and will have but little or no tendency to tilt backward to an objectionable extent in the absence of an abutting edge of the melt pot cover or additional backer bars.

The elevator will lower the ingot carrier until the projecting ends of the dumping bar 58 engage the upper rear ends of the inclined surfaces 64 of the notches in the dumping hooks 60. Such notches are so spaced above the body of molten metal that, when the dumping bar so engages the surfaces of the notches, the ingot carrier is in dumping position, partially submerged in the molten metal for from about $\frac{1}{6}$ to about $\frac{2}{3}$ of its height, and, preferably, for about $\frac{1}{2}$ of its height. This places the platform surfaces below the level of the molten metal and at least partially submerges the load of solid metal therein so that it can be dumped with a minimum of splashing of the molten metal.

The elevator then continues its downward vertical motion to cause the carrier to rotate about the pivot 26 and, at the same time, the dumping bar 58 slides down the inclined surface 64 to the bottom of the notch at 66 to compensate for the difference in distance between the dumping bar and the vertical plane of movement of the pivot 26. Such rotation of the carrier about the pivot 26 (the tilting of the carrier) brings the platform surfaces of the carrier to a final inclination of at least 30° from the horizontal and, preferably, of about 45° , as shown in dot and dash lines on Figure 2 of the drawings, whereupon the load of solid metal slides off of the platform surfaces. The sliding of the dumping bar 58 over the inclined surfaces 64 of the dumping hooks is under heavy pressures and removes any splashed metal from such surfaces or reduces the amount thereof to an insignificant thickness.

During the tilting of the carrier, the load of solid metal is brought against the bumper bar 72 and is prevented from continuing backward with the continued backward motion of the carrier platform, whereby the bumper bar nudges the load toward the forward end of the platform surfaces to aid in discharging the load from the carrier. Ordinarily, the tilting of the carrier will be sufficient to dump the load in the absence of the bumper bar. Hence, the bumper bar is not essential to the successful operation.

of the apparatus. However, if the load should not slide off the platform surfaces smoothly, but first sticks and then falls off suddenly, as is sometimes the case, excessive splashing will occur. Accordingly, it is generally preferred to provide the bumper bar so as to ensure smooth dumping of the load from the carrier.

The platform of the ingot carrier may be in the form of a single member having a large continuous flat surface extending over the entire area below the load. However, a platform of such character will be less desirable than rails because it will cause undesirable disturbance of the surface of the molten metal and will tend to accumulate solidified metal. Preferably, the platform will be in the form of a plurality of spaced longitudinally extending rails and most desirably only two rails. Such rails cause a minimum disturbance of the surface of the molten metal and present only narrow platform surfaces upon which solidified metal can accumulate and the scraping action of the load of solid metal as it slides over such surfaces during its discharge will tend to remove solidified metal on such surfaces due to the concentration of the weight of the load upon such relatively small surfaces.

After the load has been dumped from the carrier, the motion of the elevator is reversed to return the carrier to its loading position. Usually, the operation will be repeated several times until a sufficient number of loads have been charged to raise the upper surface of the body of molten metal to the desired "upper liquid level" shown in Figure 2.

As has been pointed out above, most of the operating bearing surfaces, which are likely to be splashed with molten metal, are subjected to a scraping action under high pressures which prevent the splashed metal from building up to an extent where they will render the apparatus inoperative or seriously affect its operation. The pivot 26 and the bearings therefor are also splashed, but the parts are closely fitted so that splashed molten metal cannot readily enter between them and such parts also operate under heavy pressures, whereby they are not rendered inoperative by splashing metal. The universal joint 38 is out of the range of most of the splashing metal and furthermore is shielded therefrom by the side members 32 of the crosshead. Also, such universal joint 38 may readily be provided with another shield in place of or in addition to the side members 32 of the crosshead. The apparatus of Figures 1 and 2 has been in commercial operation in charging loads of about 3800 pounds of lead into a body of molten lead for several months and has operated satisfactorily for such time with only a routine cleaning once a week.

Figure 3 shows a modified form of ingot carrier comprising two spaced vertical members 82 connected at their lower ends in the form of a U and carrying two spaced horizontal rails 84 extending transversely of such lower ends, the upper longitudinally flat surfaces of which rails form a platform surface above the lower connecting part of the U. The carrier is swingingly suspended at its upper end by a pivot 86 extending through the upper ends of the vertical members 82 slightly forward of the vertical plane of such members. Spaced parallel horizontal arms 88 extend rearwardly of the vertical members 82, slightly below the pivot 86, and carry a dumping bar 90 at their rearward ends. Such dumping bar 90 is adapted to engage one or

more dumping hooks 92 similar to the dumping hooks 60 of Figures 1 and 2. The longitudinal midpoints of the platform rails 84 will be forward of the vertical plane of the pivot 86 sufficient to balance the arms 88 and dumping bar 90, so that the center of gravity of the carrier will be substantially in the vertical plane of the pivot. Backer bars 94, carried by brackets 96, engage the rear vertical surfaces of the members 82, in the manner and for the same purposes 10 as the backer bar 76 of Figures 1 and 2.

The carrier of Figure 3 will be lowered and raised by an elevator similar to that of Figures 1 and 2 and the operation of the various parts thereof will be similar to the corresponding parts of Figures 1 and 2 as hereinbefore described.

It will be understood that the specific structures and embodiments, shown in the drawings and hereinbefore described specifically, are given for illustrative purposes solely and that variations may be made in the details of construction without departing from the spirit or scope of my invention. For example, a hydraulic cylinder may be employed in place of the pneumatic cylinder 36, or other equivalent apparatus may be used for raising and lowering the elevator and the carrier. Also, the form of construction of the elevator may be widely varied. The notches in the dumping hooks may be simple semicircular notches of a size to loosely hold the dumping bar 58, provided that the suspension of the carrier is rendered flexible as by substituting links or a cable or cables for the arms 28. The dumping hooks and the bumper bar may be adjustable vertically and the stroke of the elevator may be adjustable or the entire charging apparatus may be raised or lowered, so as to provide for changes in the predetermined level of the molten metal or in the desired degree of immersion of the carrier and load in the molten metal.

From the preceding, it will be apparent that I have provided a novel charging apparatus for charging ingots of solid metal into a body of molten metal in a melt pot, which apparatus is of simple and strong construction, is not readily rendered inoperative by splashed metal, will permit the charging of a single large ingot or one or more small ingots, is well adapted to be enclosed in a protective hood so as to protect personnel from splashing metal and obnoxious and dangerous fumes and gases, is simple and automatic in operation and permits operation by remote control. Therefore, it will be apparent that my invention constitutes a valuable advance in and contribution to the art.

I claim:

1. Apparatus for charging ingots of solid metal into a body of molten metal in a melt pot which comprises in combination an elevator for lowering an ingot carrier from a loading position above the melt pot to a dumping position at which the carrier is partially submerged in the body of molten metal for from about $\frac{1}{6}$ to about $\frac{2}{3}$ of its height and to then tilt the carrier backward to dump the ingots, an ingot carrier pivotally suspended from the bottom of the elevator, dumping means cooperating with the elevator to tilt the carrier backward as it reaches the dumping position, and backing means for preventing the ingot carrier from tilting when it is in loading position; the ingot carrier consisting essentially of two parallel spaced elongated vertical side members rigidly connected together and having smooth straight back surfaces for

most of their height, a rigid longitudinally flat horizontal platform at the lower ends of the side members, the pivotal suspension for the ingot carrier including a transverse pivot at substantially the level of the upper ends of the side members above substantially the center of gravity of the carrier; the dumping means comprising a transverse dumping bar projecting from the side members of the carrier adjacent the upper ends thereof and spaced to the rear of and extending parallel to the pivot, and at least one stationary dumping hook having a transverse notch in its upper surface above the body of molten metal at a distance equal to from about $\frac{1}{6}$ to about $\frac{1}{3}$ of the height of the ingot carrier and in the path of only the transverse dumping bar; and the backing means comprising at least one stationary backer bar above the dumping hook and opposite to and abutting the vertical straight back surfaces of the ingot carrier side members near the lower ends thereof when the ingot carrier is in loading position.

2. Apparatus for charging ingots of solid metal into a body of molten metal in a melt pot which comprises in combination an elevator for lowering an ingot carrier from a loading position above the melt pot to a dumping position at which the carrier is partially submerged in the body of the molten metal for about $\frac{1}{2}$ of its height and to then tilt the carrier backward to dump the ingots, an ingot carrier pivotally suspended from the bottom of the elevator, dumping means cooperating with the elevator to tilt the carrier backward as it reaches the dumping position, and backing means for preventing the ingot carrier from tilting when it is in loading position and until it reaches the dumping position; the ingot carrier consisting essentially of two parallel spaced elongated vertical side members rigidly connected together and having smooth straight back surfaces for most of their height, a rigid longitudinally flat horizontal platform at the lower ends of the side members, the pivotal suspension for the ingot carrier including a transverse pivot at substantially the level of the upper ends of the side members above substantially the center of gravity of the carrier; the dumping means comprising a transverse dumping bar projecting from the side members of the carrier adjacent the upper ends thereof and spaced to the rear of and extending parallel to the pivot, and at least one stationary dumping hook having a transverse notch in its upper surface above the body of molten metal at a distance equal to about $\frac{1}{2}$ of the height of the ingot carrier and in the path of only transverse dumping bar; and the backing means comprising at least one stationary backer bar above the dumping hook opposite to and abutting the vertical straight back surfaces of the ingot carrier in all positions of the ingot carrier above its dumping position.

3. Apparatus for charging ingots of solid metal into a body of molten metal in a melt pot which comprises in combination an elevator for lowering an ingot carrier from a loading position above the melt pot to a dumping position at which the carrier is partially submerged in the body of molten metal for from about $\frac{1}{6}$ to about $\frac{2}{3}$ of its height and to then tilt the carrier backward to dump the ingots, an ingot carrier pivotally suspended from the bottom of the elevator, dumping means cooperating with the elevator to tilt the carrier backward as it reaches the dumping position, and backing means for preventing the ingot carrier from tilting when it is in loading position.

ing position; the ingot carrier consisting essentially of two parallel spaced elongated vertical side members rigidly connected together and having smooth straight back surfaces for most of their height, a rigid longitudinally flat horizontal platform consisting of two spaced rails extending from front to rear of the carrier at the lower ends of the side members, the pivotal suspension for the ingot carrier including a transverse pivot at substantially the level of the upper ends of the side members above substantially the center of gravity of the carrier; the dumping means comprising a transverse dumping bar projecting from the side members of the carrier adjacent the upper ends thereof and spaced to the rear of and extending parallel to the pivot, and at least one stationary dumping hook having a transverse notch in its upper surface above the body of molten metal at a distance equal to from about $\frac{1}{6}$ to about $\frac{1}{3}$ of the height of the ingot carrier and in the path of only the transverse dumping bar, the upper edge of said notch sloping downwardly and forwardly for a few inches from the vertical plane of the dumping bar to the bottom of said notch in front of said vertical plane; and the backing means comprising at least one stationary backer bar above the dumping hook and opposite to and abutting the vertical straight back surfaces of the ingot carrier side members near the lower ends thereof when the ingot carrier is in loading position.

4. Apparatus for charging ingots of solid metal into a body of molten metal in a melt pot which comprises in combination an elevator for lowering an ingot carrier from a loading position above the melt pot to a dumping position at which the carrier is partially submerged in the body of molten metal for from about $\frac{1}{6}$ to about $\frac{1}{3}$ of its height and to then tilt the carrier backward to dump the ingots, an ingot carrier pivotally suspended from the bottom of the elevator, dumping means cooperating with the elevator to tilt the carrier backward as it reaches the dumping position, and backing means for preventing the ingot carrier from tilting when it is in loading position; the ingot carrier consisting essentially of two parallel spaced elongated vertical side members rigidly connected together and having smooth straight back surfaces for most of their height, a rigid longitudinally flat horizontal platform at the lower ends of the side members, the pivotal suspension for the ingot carrier including a transverse pivot at substantially the level of the upper ends of the side members above substantially the center of gravity of the carrier; the dumping means comprising a transverse dumping bar projecting from the side members of the carrier adjacent the upper ends thereof and spaced to the rear of and extending parallel to the pivot, at least one stationary dumping hook having a transverse notch in its upper surface above the body of molten metal at a distance equal to from about $\frac{1}{6}$ to about $\frac{1}{3}$ of the height of the ingot carrier and in the path of only the transverse dumping bar, and a stationary bumper bar of a width slightly less than the distance between the ingot carrier side members and of a height less than $\frac{1}{2}$ the height of the side members, said bumper bar being supported between the vertical planes of the side members and slightly above and to the rear of the horizontal platform surfaces of the ingot carrier when such carrier is in its lowermost untilted position; and the backing means

5 comprising at least one stationary backer bar above the dumping hook and opposite to and abutting the vertical straight back surfaces of the ingot carrier side members near the lower ends thereof when the ingot carrier is in loading position.

5. Apparatus for charging ingots of solid metal into a body of molten metal in a melt pot which comprises in combination an elevator for lowering an ingot carrier from a loading position above the melt pot to a dumping position at which the carrier is partially submerged in the body of molten metal for from about $\frac{1}{6}$ to about $\frac{1}{3}$ of its height and to then tilt the carrier backward to dump the ingots, an ingot carrier pivotally suspended from the bottom of the elevator, dumping means cooperating with the elevator to tilt the carrier backward as it reaches the dumping position, and backing means for preventing the ingot carrier from tilting when it is in loading position; the ingot carrier consisting essentially of two parallel spaced vertical side members each substantially in the form of a vertically elongated square C 10 having a smooth straight back surface extending vertically for most of its height and in which the lower horizontally extending portion has an upper longitudinally flat horizontal platform surface, spacer members rigidly connecting the lower horizontally extending portions of the side members 15 20 25 30 35 40 45 50 55 60 65 70 75 80 surface, spacer members rigidly connecting the lower horizontally extending portions of the side members together below the upper platform surfaces of the lower horizontally extending portions of the side members, the pivotal suspension for the ingot carrier including a transverse pivot extending through the upper horizontally extending portions of the side members intermediate the ends thereof and above substantially the center of gravity of the carrier; the dumping means comprising a transverse dumping bar projecting from the side members of the carrier adjacent the upper rear corners thereof and extending parallel to the pivot, and stationary dumping hooks having transverse notches in their upper surfaces above the body of molten metal at a distance equal to about $\frac{1}{2}$ of the height of the ingot carrier and in the path of only the transverse dumping bar; and the backing means comprising at least one stationary bumper bar above the dumping hooks and opposite to and abutting the vertical straight back surfaces of the ingot carrier in all positions of the ingot carrier above its dumping position.

7. Apparatus for charging ingots of solid metal into a body of molten metal in a melt pot which comprises in combination an elevator for lowering an ingot carrier from a loading position above the melt pot to a dumping position at which the carrier is partially submerged in the body of molten metal for from about $\frac{1}{6}$ to about $\frac{1}{3}$ of its height and to then tilt the carrier backward to dump the ingots, an ingot carrier pivotally suspended from the bottom of the elevator and having a horizontal platform consisting of two spaced rails extending from front to rear thereof, dumping means cooperating with the elevator to tilt the carrier backward as it reaches the dumping position, and backing means for preventing the ingot carrier from tilting when it is in loading position; the ingot carrier consisting essentially of two parallel spaced vertical side members each substantially in the form of a vertically elongated square C having a smooth straight back surface extending vertically for most of its height and in which the lower horizontally extending portion has an upper longitudinally flat horizontal platform surface and forms a rail of the carrier platform, spacer members rigidly connecting the lower horizontally extending portions of the side members together below the horizontal plane of the plane of the upper platform surfaces of the lower horizontally extending portions of the side members, the pivotal suspension for the ingot carrier including a transverse pivot extending through the upper horizontally extending portions of the side members intermediate the ends thereof and above substantially the center of gravity of the carrier; the dumping means comprising a transverse dumping bar projecting from the side members of the carrier adjacent the upper rear corners thereof and extending parallel to the pivot, and stationary dumping hooks having transverse notches in their upper surfaces above the body of molten metal at a distance equal to from about $\frac{1}{6}$ to about $\frac{1}{3}$ of the height of the ingot carrier and in the path of only the transverse dumping bar, the upper edge of each notch sloping downwardly and forwardly for a few inches from the vertical plane of the dumping bar to the bottom of said notch in front of said vertical plane; and the backing means comprising at least one stationary bumper bar above the dumping hooks and opposite to

and abutting the vertical straight back surfaces of the ingot carrier near the lower ends thereof when the ingot carrier is in loading position.

8. Apparatus for charging ingots of solid metal into a body of molten metal in a melt pot which comprises in combination an elevator for lowering an ingot carrier from a loading position above the melt pot to a dumping position at which the carrier is partially submerged in the body of molten metal for from about $\frac{1}{6}$ to about $\frac{1}{3}$ of its height and to then tilt the carrier backward to dump the ingots, an ingot carrier pivotally suspended from the bottom of the elevator and having a horizontal platform consisting of two spaced rails extending from front to rear thereof, dumping means cooperating with the elevator to tilt the carrier backward as it reaches the dumping position, and backing means for preventing the ingot carrier from tilting when it is in loading position; the ingot carrier consisting essentially of two parallel spaced vertical side members each substantially in the form of a vertically elongated square C having a smooth straight back surface extending vertically for most of its height and in which the lower horizontally extending portion has an upper longitudinally flat horizontal platform surface and forms a rail of the carrier platform, spacer members rigidly connecting the lower horizontally extending portions of the side members together below the horizontal plane of the upper platform surfaces of the lower horizontally extending portions of the side members, the pivotal suspension for the ingot carrier including a transverse pivot extending through the upper horizontally extending portions of the side members intermediate the ends thereof and above substantially the center of gravity of the carrier; the dumping means comprising a transverse dumping bar projecting from the side members of the carrier adjacent the upper rear corners thereof and extending parallel to the pivot, and stationary dumping hooks having transverse notches in their upper surfaces above the body of molten metal at a distance equal to from about $\frac{1}{6}$ to about $\frac{1}{3}$ of the height of the ingot carrier and in the path of only the transverse dumping bar; and a stationary bumper bar of a width slightly less than the distance between the ingot carrier side members and of a height less than $\frac{1}{2}$ the height of the side members, said bumper bar being supported between the vertical planes of the side members and slightly above and to the rear of the horizontal platform surfaces of the ingot carrier when such carrier is in its lowermost untilted position; and the backing means comprising at least one stationary bumper bar above the dumping hooks and opposite to and abutting the vertical straight back surfaces of the ingot carrier near the lower ends thereof when the ingot carrier is in loading position.

9. Apparatus for charging ingots of solid metal into a body of molten metal in a melt pot which comprises in combination an elevator for lowering an ingot carrier from a loading position above the melt pot to a dumping position at which the carrier is partially submerged in the body of molten metal for from about $\frac{1}{6}$ to about $\frac{1}{3}$ of its height and to then tilt the carrier backward to dump the ingots, an ingot carrier pivotally suspended from the bottom of the elevator, dumping means cooperating with the elevator to tilt the carrier backward as it reaches the dumping position, stop means for preventing the ingot carrier from tilting forwardly, and

backing means for preventing the ingot carrier from tilting backwardly when it is in loading position; the ingot carrier consisting essentially of two parallel spaced vertical side members each substantially in the form of a vertically elongated square C having a smooth straight back surface extending vertically for most of its height and in which the lower horizontally extending portion has an upper longitudinally flat horizontal platform surface, spacer members rigidly connecting the lower horizontally extending portions of the side members together below the horizontal plane of the upper platform surfaces of the lower horizontally extending portions of the side members, the pivotal suspension for the ingot carrier including a transverse pivot extending through the upper horizontally extending portions of the side members intermediate the ends thereof and above substantially the center of gravity of the carrier; the dumping means comprising a transverse dumping bar projecting from the side members of the carrier adjacent the upper rear corners thereof and extending parallel to the pivot, and stationary dumping hooks having transverse notches in their upper surfaces above the body of molten metal at a distance equal to from about $\frac{1}{6}$ to about $\frac{1}{3}$ of the height of the ingot carrier and in the path of only the transverse dumping bar; the stop means comprising stop arms on the elevator extending forwardly of the carrier pivot immediately above the upper horizontally extending portions of the side members; and the backing means comprising at least one stationary backer bar above the dumping hooks and opposite to and abutting the vertical straight back surfaces of the ingot carrier near the lower ends thereof when the ingot carrier is in loading position.

10. Apparatus for charging ingots of solid metal into a body of molten metal in a melt pot which comprises in combination an elevator for lowering an ingot carrier from a loading position above the melt pot to a dumping position at which the carrier is partially submerged in the body of molten metal for from about $\frac{1}{6}$ to about $\frac{1}{3}$ of its height and to then tilt the carrier backward to dump the ingots, an ingot carrier pivotally suspended from the bottom of the elevator and having a horizontal platform consisting of two spaced rails extending from front to rear thereof, dumping means cooperating with the elevator to tilt the carrier backward as it reaches the dumping position, stop means for

preventing the ingot carrier from tilting forwardly, and backing means for preventing the ingot carrier from tilting backwardly when it is in loading position; the ingot carrier consisting essentially of two parallel spaced vertical side members each substantially in the form of a vertically elongated square C having a smooth straight back surface extending vertically for most of its height and in which the lower horizontally extending portion has an upper longitudinally flat horizontal platform surface and forms a rail of the carrier platform, spacer members rigidly connecting the lower horizontally extending portions of the side members together below the horizontal plane of the upper platform surfaces of the lower horizontally extending portions of the side members, the pivotal suspension for the ingot carrier including a transverse pivot extending through the upper horizontally extending portions of the side members intermediate the ends thereof and above substantially the center of gravity of the carrier; the dumping means comprising a transverse dumping bar projecting from the side members of the carrier adjacent the upper rear corners thereof and extending parallel to the pivot, and stationary dumping hooks having transverse notches in their upper surfaces above the body of molten metal at a distance equal to from about $\frac{1}{6}$ to about $\frac{1}{3}$ of the height of the ingot carrier and in the path of only the transverse dumping bar, the upper edge of each notch sloping downwardly and forwardly for a few inches from the vertical plane of the dumping bar to the bottom of said notch in front of said vertical plane; the stop means comprising stop arms on the elevator extending forwardly of the carrier pivot immediately above the upper horizontally extending portions of the side members; and the backing means comprising at least one stationary backer bar above the dumping hooks and opposite to and abutting the vertical straight back surfaces of the ingot carrier near the lower ends thereof when the ingot carrier is in loading position.
